CLAIM

The ornamental design for a clasp for bags, as shown and described.

DESCRIPTION

1. Clasp for bags

1.1 is a front perspective view of the clasp for bags showing my new design;

1.2 is a front view thereof;

1.3 is a rear view thereof;

1.4 is a right side view thereof;

1.5 is a left side view thereof;

1.6 is a top plan view thereof;

1.7 is bottom plan view thereof; and

1.8 is another perspective view thereof, with the clasp shown in a separated condition of use.

The broken lines in the drawings depict portions of the clasp for bags that form no part of the claimed design.
